(57) **CLAIM**

The ornamental design for a packaging machine, as shown and described.

DESCRIPTION

FIG. 1 is a perspective view of top, front, and left side of a first embodiment of a packaging machine;

FIG. 2 is a front view thereof;

FIG. 3 is a right side view thereof;

FIG. 4 is a left side view thereof;

FIG. 5 is a top plan view thereof;

FIG. 6 is a rear view thereof; and,

FIG. 7 is another perspective view of top, front, and right side thereof.

The unillustrated portions of the bottom are plain and form no part of the claimed design.
